Primary Examiner — David Muller*Assistant Examiner* — Nathan Johnston(74) *Attorney, Agent, or Firm* — McDonnell Boehnen Hulbert & Berghoff LLP(57) **CLAIM**

The ornamental medicament injection device, as shown and described.

DESCRIPTION

FIG. 1 is a perspective view of the injection device with a cap portion attached to a distal portion of a main housing viewed from the front and left of and above the injection device;
FIG. 2 is a front end elevation view thereof;
FIG. 3 is a rear end elevation view thereof;
FIG. 4 is a top plan view thereof;
FIG. 5 is a bottom plan view thereof;
FIG. 6 is a left side elevation view thereof; and,
FIG. 7 is a right side elevation view thereof.

The broken line showing of parts of the drawings is included for the purpose of illustrating use and environment and forms no part of the claimed design.
